ROTOR FOR RAILWAY COUPLER

Loree Elwyn Furniss, Groveport, Ohio, assignor to The Buckeye Steel Castings Company, Columbus, Ohio
Filed July 2, 1959, Ser. No. 824,563
3 Claims. (Cl. 213—133)

The present invention relates to the rotor element for a railway coupler of the knuckle type which forms a part of the mechanism for releasing the anticreep and lifting the lock and the invention more specifically pertains to structural characteristics of the outer end portion of the rotor which receives the hook shaped inner end portion of a coupler operating rod.

The interlocking type coupler has provided important safety features in the operation of railway vehicles and a desired attribute of such couplers is that they remain in coupled relationship in cases of accidents. It has been found that outward movement of a coupler with respect to the body structure of a railway vehicle as a consequence of a structural failure causes the present type of rotor employed in the type F coupler to be turned in a direction of rotation to free the anticreep mechanism and to lift the lock sufficiently for the knuckle to swing to an open position. Such unintentional unlocking of the coupler renders the safety features of interlocking type couplers ineffective and it is possible for the unlocked coupler to fall to the roadbed. The outer end of the coupler operating rod is journaled for rotation on the railway vehicle body and the hook shaped inner end portion in its engagement with the eye of present standard type rotor develops torque on the rotor during outward movement of the coupler with respect to the railway vehicle body to provide an undesired lifting of the lock which permits the couplers to be parted.

It is an object of the present invention to provide structural features at the outer end of the rotor for connection with the operating rod whereby the undesired unlocking of the coupler is avoided during outward movement of the coupler with respect to the vehicle body and to provide a rotor which may be readily cast without the use of cores in forming the eyelet portion of the rotor.

Other objects and features of the invention will be appreciated and become apparent particularly to those skilled in the railway coupler art as the present disclosure proceeds and upon consideration of the following detailed description taken with the accompanying drawings wherein an embodiment of the invention is disclosed.

In the drawings:

FIG. 1 is a perspective view of a rotor for the lock operating mechanism of a railway coupler having an eyelet portion embodying the invention.

FIG. 2 is a sectional view taken on the line 2—2 of FIG. 1.

FIG. 3 is an end elevation of the rotor showing the cooperation of the hook shaped inner end portion of the coupler operating rod with the rotor at the initiation of an intended lock lifting operation.

FIG. 4 is a rear elevation of the outer end or eyelet portion of the rotor with the coupler operating rod in the position shown in FIG. 3.

FIG. 5 is an elevational view of the rotor showing the position of the coupler operating rod in relation to the eyelet portion after the coupler has moved outwardly with respect to a railway vehicle body.

FIG. 6 is a plan view of the eyelet portion of the rotor with the coupler operating rod in the position shown in FIG. 5.

FIG. 7 is an end elevation of the rotor showing the position of the coupler operating rod in relation to the eyelet portion after the coupler has moved outwardly with

2

respect to the vehicle body beyond the position shown in FIG. 5.

FIG. 8 is a plan view of the eyelet portion of the rotor with the coupler operating rod in the position shown in FIG. 7.

FIG. 9 is an end view of the rotor in the rotated position it assumes after the coupler has been unlocked, the knuckle fully opened, and the rotor has turned clockwise until the lock is supported on the tail of the knuckle and with the coupler operating rod in the inactive position it assumes when the handle is against the stop on its support bracket.

FIG. 10 is an end view of the rotor in the inactive position illustrating the coupler operating rod in the inactive position.

FIG. 11 is a plan view of the eyelet portion showing the free angling positions of the rotor relative to the coupler operating rod.

FIG. 12 is a sectional view taken on the line 12—12 of FIG. 1.

The invention pertains to the structural characteristics of the outer end portion of the rotor element for the lock operating mechanism of a railway coupler. The shaft portion 14 is provided with a lug 15 projecting therefrom and the lug is provided with flat opposite faces 16 and 17. The shaft portion 14 and the structure of the lug 15 are of conventional construction and the rotor while being particularly adapted for the type F coupler may be used in other couplers. The structural characteristics of the outer end or eyelet portion 18 (FIG. 1) of the rotor provides new results in its cooperation with the hook shaped inner end portion of a conventional coupler operating rod 19. The geometrical axis of the shaft portion 14 is indicated at 20 and it is this axis about which the element rotates in operating the lock.

The rotor is shown in the inactive position in FIG. 10 and in this position substantially all parts making up the eyelet portion are disposed below the axis 20 of rotation of the rotor. The eyelet portion includes an arm 21 which is disposed substantially at right angles to the axis of the shaft portion 14 and extends forwardly therefrom. The arm 21 is formed integral with the shaft portion 14 and has an upper surface 22 which is substantially straight and disposed in a plane which is tangential to the periphery of the shaft portion 14. The undersurface 23 of the arm 21 in the area forwardly of the shaft portion 14 is substantially straight but the surfaces 22 and 23 converge towards each other in proceeding forwardly.

The eyelet portion 18 of the rotor includes a front element 26 formed integral with the forward end of the arm 21 and extending outwardly therefrom in a direction generally parallel to the axis of the shaft portion 14. The front element 26 has a rear surface 27 which is convex viewed in vertical section as shown in FIG. 2. The eyelet portion includes a rear element 28 which is formed integral with the outer end of the shaft portion 14 and extends outwardly therefrom. The rear element 28 has substantially all portions thereof located below and rearwardly of the geometrical axis 20 of the shaft portion. The rear element 28 in general extends outwardly in a direction generally parallel with the axis of the shaft portion 14. The rear element 28 has a convex surface 29 viewed in vertical section as shown in FIG. 2 and the element 28 is generally cylindrical in section in the mid portion thereof.

The outer ends of the front element 26 and the rear element 28 are joined by a side member 31 which is in general substantially parallel to the arm 21. The side member 31 has structural characteristics and surfaces thereon which provide improved results in cooperation with the hook shaped inner end portion of the coupler operating rod 19. The side member 31 is formed integral with the outer ends of the front element 26 and the rear element 28.

The side member 31 has a flat upper surface 32 and this surface provides a bearing area for the portion 42 of the coupler operating rod 19 adjacent the hook shaped inner end as shown in FIG. 10. Rearwardly of the flat surface 32 the side member carries an integral hump 33 having an upper surface 34 which is substantially flat and while being substantially parallel with the surface 32 lies in a plane above the surface 32. A shoulder 36 carried by the side member 31 is formed between the surfaces 32 and 34. The forward face of the shoulder 36 is convex shaped in plan as shown in FIGS. 1 and 6.

The side member 31 forwardly of the geometrical axis 20 has an outer face 38 which may be flat and arranged in a plane substantially at right angles to the axis of the shaft portion 14. The undersurface of the forward portion of the side member 31 has a straight surface 39 which lies in a plane substantially at right angles to the side face 38. The surface 39 diverges from the surface 32 in proceeding forwardly of the side member 31. In the inactive position of the rotor the surface 39 slopes downwardly in proceeding forwardly. The inner surface of the side member 31 particularly in the portions which join the front element 26 and the rear element 28 are of arcuate formation viewed in plan and merge with corresponding surfaces of the front element 26 and the rear element 28. An elongated opening is provided in the structure which forms the outer end or eyelet portion 18 for receiving the hook shaped inner end portion of the coupler operating rod.

The inactive portion of the rotor and the coupler operating rod 19 is shown in FIG. 10 and it will be observed that there is clearance between the lower free end 41 of the hook shaped end of the coupler operating rod 19 and the inclined surface 39. In the inactive position of the rotor and the coupler operating rod there may be an angular displacement of the axis of the shaft portion 14 of the rotor with respect to the axis of the coupler operating rod 19 by as much as eighteen degrees in either direction as depicted in FIG. 11 without development of any turning movement of the rotor about the axis 20. This free swiveling is sufficient for practically all operating conditions.

In carrying out an intended unlocking of the coupler and when the handle carried by the outer end of the coupler operating rod 19 is raised counter-clockwise rotation is imparted to the rod and the lower free end portion 41 of the rod moves from the position shown in FIG. 10 to the position shown in FIG. 3. The portion 41 of the rod engages the inclined undersurface 39 of the side member 31 and the upper portion 42 of the hook shaped end which is supported on the surface 32 of the side member 31 contacts the shoulder 36. A force F and a force F1 will be developed on the hook shaped end portion of the coupler operating rod and these forces will be equal in magnitude and opposite in direction as will be appreciated from a consideration of FIG. 3. The force F acts at right angles to the inclined surface 39 and the force F1 acts parallel to the force F but in the opposite direction at a point in the pocket between the shoulder 36 and the surface 32 where the interengaging surfaces are perpendicular to the line of force F1. Any movement of the hook shaped end of the coupler operating rod with respect to the eyelet portion of the rotor from this position of static equilibrium will cause the direction of the force F1 to be changed. This changes the magnitude of the horizontal and vertical components of the force F1 thereby producing instability where the lower portion 41 of the hook shaped end engages the surface 39. Thus the inner end portion of the coupler operating rod 19 will remain in contact with the shoulder 36 and as the counter-clockwise rotation of the coupler operating rod is continued the rotor will be turned to operate the release of the antcreep mechanism to lift the lock and throw the knuckle to an open position.

In the event of a structural failure in the draft rigging so that the coupler moves outwardly with respect to the

vehicle body beyond the limit permitted by the resilient draft gear the angular disposition of the rotor with respect to the coupler operating rod will assume a position somewhat as shown in FIGS. 5 and 6. Two forces F2 and F3 will be developed on the inner end portion of the coupler operating rod 19 where it engages the rotor eyelet. The force F3 is normal to the engagement of the coupler operating rod with the surface 27 of the forward element 26 and this force will be in a substantially horizontal direction. The force F2 will be normal to the engagement of the shoulder 36 and the coupler operating rod as shown in FIG. 5 but the force F2 is applied in an upward direction against the portion 42 of the coupler operating rod. As the forces F2 and F3 increase the vertical component of the force F2 will increase until it overcomes the friction and the weight of the inner end portion of the coupler operating rod. The portion 42 of the coupler operating rod will then be raised to overlie the surface 34 and the coupler operating rod is free for swiveling with respect to the rotor as it is supported on the surface 34. The coupler operating rod is thus supported on the rear element 28 and continued outward movement of the coupler head and the rotor with respect to the vehicle body is possible without developing any prying forces or torque between the coupler operating rod and the rotor.

A continuation of the pull-out of the coupler will develop a condition as shown in FIGS. 7 and 8 wherein the operating rod 19 assumes a position with its axis at approximately ninety degrees with respect to the axis of the shaft portion 14 but such position of the parts does not develop any counter-clockwise torque on the rotor. The hook-shaped end will pull rearwardly on the rear element 28 of the eyelet portion to provide a force F4. The point of contact of the coupler operating rod with the rear element 28 is below the geometrical axis or center 20 of the shaft portion 14. Since the only movement of the rotor possible is rotation of the shaft portion 14 with respect to the coupler head and since the rotor is restricted from moving clockwise from the inactive position by the coupler parts (not shown) the forces F4 and F6 as shown in FIG. 7 create a resulting clockwise moment which holds the lock operating mechanism in the locked position.

The eyelet portion of the rotor provides further improvements in intended operation of the lock actuating elements of a coupler. When the coupler is unlocked and the knuckle is in the fully open position the rotor when released will rotate in a clockwise direction until the parts come to rest with the lock supported on the tail of the knuckle. The rotor then assumes the position illustrated in FIG. 9. The hook shaped end of the coupler operating rod then assumes the inactive position shown with the handle at the outer end in engagement with its supporting bracket stop. Under these operating conditions the weight W of the inner end of the coupler operating rod is applied to the rotor a distance D from the center of rotation. A moment arm WD is thus provided which acts to help rotate the rotor and facilitate the dropping of the lock into the locked position when the knuckle is closed.

A rotor provided with an eyelet portion 18 in addition to avoiding undesired freeing of the antcreep and lifting of the lock on an accidental pull-out of the coupler also avoids malfunctioning when used in a coupler having a long travel draft gear. The lower portion 41 of the hook shaped inner end of the coupler operating rod having clearance with the inclined surface 39 as shown in FIG. 10 provides an arrangement wherein the operating rod is free to swivel approximately eighteen degrees in either direction as shown in FIG. 11. Such free swiveling movement of the coupler operating rod with respect to the shaft portion 14 of the rotor avoids any tendency of the lock operating mechanism to be actuated as a consequence of outward movement of the coupler with respect to the vehicle body as permitted by long travel

resilient draft gears. The rotor may be readily cast in foundry operations without the necessity of providing cores and the improved rotor provides the further advantage of a reduction in the weight of the rotor.

While the invention has been described with regard to a rotor for a type F coupler it will be appreciated that this element of the lock operating mechanism may be employed in other couplers and that changes may be made in the structural characteristics of the rotor. Such modifications and others may be made without departing from the spirit and scope of the invention as set forth in the appended claims.

What I claim and desire to secure by Letters Patent is:

1. In a lock operating mechanism for a railway coupler, a rotor having a shaft portion supportable on a coupler for rotation about the axis of the shaft portion from an inactive position to a position for unlocking the coupler, an eyelet portion carried by the outer end of said shaft portion, said eyelet portion including a side member disposed generally transversely of the shaft portion and spaced from the outer end thereof, an upwardly facing substantially flat surface on said side member disposed below and forwardly of said axis in the inactive position of the rotor, a second upwardly facing surface on said side member rearwardly of and positioned above the first surface and substantially at the level of said axis in the inactive position of the rotor, a generally vertical shoulder defining the rear end of said first upwardly facing surface and the forward end of said second upwardly facing surface with the upper end of said shoulder being substantially in alignment with the axis of said shaft portion, a downwardly facing surface on the side member in the inactive position of the rotor diverging from said first surface in proceeding forwardly, a coupler

operating rod overlying said first surface and having a hook-shaped part extending through the eyelet portion with the end portion of the rod underlying said downwardly facing surface, said rod engageable with said shoulder and said end portion engageable with said downwardly facing surface during rotation of the rod about its longitudinal axis to turn the rotor about its axis from the inactive position towards the coupler unlocking position, a second downwardly facing surface on said side member rearwardly of the first downwardly facing surface in the inactive position of the rotor spaced from the second upwardly facing surface less than the space provided between the rod and the end portion thereof, and said eyelet portion including a rear element having a forwardly facing surface positioned below said axis in the inactive position of the rotor engageable by the hook-shaped part of said rod upon swinging movement of the rod relative to the rotor about a generally vertical axis.

2. In a lock operating mechanism for a railway coupler according to claim 1 wherein the shoulder is concave shaped viewed in side elevation.

3. In a lock operating mechanism for a railway coupler according to claim 1 wherein the forwardly facing surface on the rear element is convex shaped viewed in side elevation.
